UNITED STATES PATENT OFFICE

GEORGE WALTER DUNNICKAN, OF BLOOMFIELD, NEW JERSEY, ASSIGNOR TO WEIMANN BROS. MANUFACTURING COMPANY, OF DERBY, CONNECTICUT, A CORPORATION OF CONNECTICUT

CLIP FOR COLLAPSIBLE TUBES

Application filed August 24, 1929. Serial No. 388,222.

This invention relates to collapsible tubes for containing and dispensing tooth paste, shaving cream, or the like, and more particularly to a clip for locking the flat end of such a collapsible tube.

One object of this invention is to provide a paste tube clip which will be very securely attached to the flat end of the tube and yet will not pierce or puncture the metal thereof.

10 A further object is to provide a device of the above nature which will be simple in construction, inexpensive to manufacture, easy to install and manipulate, compact, rigid, ornamental in appearance, and very efficient and durable in use.

With these and other objects in view there have been illustrated on the accompanying drawing several forms in which the invention may be conveniently embodied in practice.

20 Fig. 1 represents a plan view of a collapsible tube having applied thereto a clip of the first form embodying the invention.

Fig. 2 is a plan view on an enlarged scale of a portion of the clip shown in Fig. 1.

25 Fig. 3 is an interior end view of the same.

Fig. 4 is a side sectional view taken along the line 4—4 of Fig. 2.

30 Fig. 5 is a plan view of a modified form of clip having a pair of staggered indentations at each end thereof and providing a space between said indentations for receiving printed matter.

Fig. 6 is a plan view of a modified form 35 of clip, similar to the clip shown in Fig. 5 but employing three indentations at each end thereof.

Fig. 7 is a plan view of a modified form of wide clip adapted to be used on large tubes.

40 It has been customary in the past to secure the locking clips of collapsible tubes in position on the flat ends of such tubes by means of cooperating sets of indentations in the clip situated opposite each other. One indentation of each set was generally a point and the other indentation a socket fitting about said point. It was found in practice, however, that this form of construction was easily bent out of shape and was quite apt 45 to puncture the soft metal of the tube. It

was also expensive to manufacture such clips. By means of the present invention the above and other disadvantages have been avoided. This has been accomplished by providing a locking clip having the indentations 55 on the opposite sides thereof out of alignment with each other, or staggered. The indentations are elongated to provide stiffness for preventing bending, and the adjacent ends thereof are located sufficiently close to 60 grip the metal of the tube securely but without danger of puncturing it. In addition, this construction is much cheaper to manufacture than the former types of clips.

Referring now to the drawing in which 65 like reference numerals denote corresponding parts throughout the several views, the numeral 10 indicates a collapsible tube for containing paste to be dispensed through a neck 11, after the cap 11^a is removed, by squeezing 70 the cylindrical part 12 thereof. The end 13 of the tube opposite from the neck 11 is flat and is adapted to be locked by a U-shaped clip 14 having opposing substantially parallel sides 15 and 16. Extending inwardly 75 from both sides 15 and 16 are a plurality of equispaced indentations 17, 18, 19 and 20, 21, 22, respectively. As most clearly shown in Figs. 2, 3, and 4, each of the indentations is elongated and of substantially rectangular 80 form having rounded ends and being slightly pointed or tapered in order to form a secure grip upon the metal of the tube located therebetween.

In the modified form of clip 22^a shown in 85 Fig. 5, a pair of opposed cooperating indentations 23, 24 and 25, 26 are provided at the ends only, leaving a section 27 therebetween on which any desired lettering may be stamped.

90 In Fig. 6 another modified form of the invention is shown, this clip 28 being similar to the clip of Fig. 5 with the exception that three cooperating indentations 29, 30, 31 and 32, 33, 34 are provided at the ends of the 95 clip 28.

A still further modified form of locking clip 35 is illustrated in Fig. 7. This clip is made considerably wider and longer than the first form shown in Fig. 1 and instead of six 100

alternating staggered indentations, the clip shown in Fig. 7 has nine of such indentations numbered 36, 37, 38, 39, 40, 41, 42, 43, 44, respectively.

While there have been disclosed in this specification several forms in which the invention may be embodied it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

- 20 1. In a clip for clamping about the sides of the flat end of a collapsible tube, a strip of metal bent into U-shape forming a pair of jaws to embrace said flat end, said jaws having a plurality of alternating, elongated, staggered indentations extending longitudinally of the clip for engaging the metal of said tube and preventing lateral and longitudinal movement of said clip.
- 25 2. In a clip for clamping about the sides of the flat end of a collapsible tube, a strip of metal bent into U-shape forming a pair of jaws to embrace said flat end, said jaws having a plurality of alternating, elongated, staggered indentations extending longitudinally of the clip for engaging the metal of said tube and preventing lateral and longitudinal movement of said clip, each of said indentations being tapered to provide pointed teeth for gripping the soft metal of the tube.
- 30 3. In a clip for clamping about the sides of the flat end of a collapsible tube, a strip of metal bent into U-shape forming a pair of jaws to embrace said flat end, said jaws having a plurality of alternating, elongated staggered indentations extending longitudinally of the clip for engaging the metal of said tube and preventing lateral and longitudinal movement of said clip, the central section of said clip being left free from indentations to provide a space for receiving stamped figures.
- 35 4. In a clip for clamping about the sides of the flat end of a collapsible tube, a strip of metal bent into U-shape forming a pair of jaws to embrace said flat end, said jaws having a plurality of alternating, elongated, staggered indentations extending longitudinally of the clip for engaging the metal of said tube and preventing lateral and longitudinal movement of said clip, the extremities of said indentations being rounded.
- 40 5. In a clip for clamping about the sides of the flat end of a collapsible tube, a strip of metal bent into U-shape forming a pair of

jaws to embrace said flat end, said jaws having a plurality of alternating, elongated, staggered indentations extending longitudinally of the clip for engaging the metal of said tube and preventing lateral and longitudinal movement of said clip, the ends of adjacent opposed indentations being located close together to afford a strong grip upon the tube.

In testimony whereof, I have affixed my signature to this specification.

GEORGE WALTER DUNNICAN.
